(57) **CLAIM**

I claim the ornamental design for the lever latch for a tool, as shown and described.

DESCRIPTION

FIG. 1 is a perspective view of a lever latch for a tool; FIG. 2 is a front view of the lever latch for a tool shown in FIG. 1, with the rear view being a mirror image; FIG. 3 is a top view of the lever latch for a tool shown in FIG. 1; FIG. 4 is a right side view of the lever latch for a tool shown in FIG. 1; FIG. 5 is a left side view of the lever latch for a tool shown in FIG. 1; and, FIG. 6 is a bottom view of the lever latch for a tool shown in FIG. 1. The broken lines showing portions of the tool in FIGS. 1-6 are for illustrative purposes only and form no part of the claimed design.
